[57] CLAIM

The ornamental design for a rod for unlocking and locking a vehicle door, as shown.

DESCRIPTION

FIG. 1 is a longitudinal elevational view of the rod for unlocking and locking a vehicle door of the present invention;

FIG. 2 is a view similar to FIG. 1 with the rod rotated in a first direction 90° about its longitudinal axis;

FIG. 3 is a view similar to FIG. 1 with the rod rotated in a second direction 90° about its longitudinal axis;

FIG. 4 is an elevational view at an enlarged scale of the left end of the rod as seen in FIG. 1;

FIG. 5 is a vertical, transverse sectional view at an enlarged scale taken along line 5—5 of FIG. 2; and

FIG. 6 is an elevational view at an enlarged scale of the forked end of the rod.
